Milton R. Stohl, Greenwich, Conn., assignor to Borden, Inc., New York, N.Y., a corporation of New Jersey

Filed Aug. 4, 1967, Ser. No. 8,125

Term of patent 14 years

(Cl. D85—2)

FIG. 1

FIG. 5

FIG. 2

FIG. 3

FIG. 4

FIG. 1 is a perspective view of a combined ash tray and tape dispenser, showing my new design;

FIG. 2 is a right side elevational view, the left side elevational view being a mirror image thereof;

FIG. 3 is a front elevational view;

FIG. 4 is a rear elevational view; and

FIG. 5 is a bottom plan view.

The dominant features of my design reside in the portions shown in solid lines, conventional feet being shown in broken lines.

I claim:

The ornamental design for a combined ash tray and tape dispenser, substantially as shown and described.
